UNITED STATES PATENT OFFICE.

GEORGE E. HUNTER AND FREDERICK H. CORTHELL, OF ELGIN, ASSIGNORS
TO THE ELGIN NATIONAL WATCH COMPANY, OF CHICAGO, ILLINOIS.

METHOD OF ADJUSTING WATCHES.

SPECIFICATION forming part of Letters Patent No. 437,203, dated September 30, 1890.

Application filed September 23, 1889. Serial No. 324,820. (No model.)

To all whom it may concern:

Be it known that we, GEORGE E. HUNTER and FREDERICK H. CORTHELL, of Elgin, in the County of Kane, and in the State of Illinois, have invented certain new and useful Improvements in the Method of Adjusting Watches; and we do hereby declare that the following is a full, clear, and exact description thereof, reference being had to the accompanying drawings, in which—

Figure 1 is a perspective view of our recording mechanism. Figs. 2 and 3 are respectively enlarged side and end elevations of the same. Fig. 4 is an enlarged plan view of the upper end of the vibratile reed and the wheel engaged by the same. Fig. 5 is a like view of the mechanism employed for connecting and disconnecting the reed-engaged wheel with the recording mechanism, and Fig. 6 is a perspective view of the mechanism employed for vibrating a balance in connection with the recording mechanism.

Letters of like name and kind refer to like parts in each of the figures.

25 In the manufacture of watches much difficulty has heretofore been experienced in the selection of balances and hair-springs which are adapted for use in a movement, and by the methods and mechanism in use the desired result could only be approximated.

The object of our invention is to render practicable the selection of a balance and a hair-spring which when combined in a watch-movement shall be so nearly adapted 35 for joint use and for the particular movement as to render the rate of the same substantially correct; and to this our said invention consists in the method employed, substantially as and for the purpose hereinafter 40 specified.

In the carrying of our invention into practice the suitability of a balance is determined by causing it to vibrate a predetermined number of times in connection with a standard 45 hair-spring and a suitable train and noting the time required for such vibrations, which period of time is divided into a great number of parts, so as to permit of a fine and accurate measurement of the time consumed, not only 50 by a single vibration, but by any fraction of such vibration.

For the purpose of vibrating a balance A we preferably employ an ordinary time-train, which is inclosed within a suitable casing B and actuated by a spring or weight. The 55 balance-arbor C projects above the said casing, and is provided with a hair-spring D of standard strength, and is adapted to receive and carry a balance and to permit of the easy placing in or removing of the same from position. The time-train is provided with ordinary stop mechanism, which may be released by a push-button E, and when so released will permit the train to run until a certain number of vibrations have been made by the 65 balance, when further motion will be automatically arrested. The construction of said vibrating mechanism will be readily understood and requires no special description.

For measuring the length of time required 70 for the vibrations of the balance A we employ a vibratile reed F, which is constructed from soft iron and has one of its ends secured within a suitable base G, from whence said reed projects upward, as shown. For the purpose of determining and varying the operative length of said reed its lower portion passes through a fulcrum-block H, which closely embraces and is adjustable lengthwise of the same, and is supported by or upon a 80 standard G', that extends upward from the base G. Upon opposite sides of the reed F are placed electro-magnets I and I', which are suitably connected with a source of electric energy and operate by alternate attraction to 85 give to said reed a vibratory motion in substantially the same manner as in case of the hammer of an electric bell. The length of time required for each vibration is determined by the operative length of said reed, and is 90 in no manner dependent upon the strength of the electric current, so that an absolutely uniform rate of motion is obtained by the action of a current having sufficient strength to set the reed in motion. Said electro-magnets 95 are adjustably connected with a suitable support, so that the distance between their poles may be varied at will, so as to enable them to act most efficiently upon said reed.

Changes of temperature may vary the operative length of the reed F and so change the rate of its movements; but such changes

may be compensated for by adjusting the fulcrum-block II until the sound produced by said reed has the required pitch, as determined by comparison with a tuning-fork, 5 pitch-pipe, or other standard.

The vibrating motion of the reed F is utilized to give motion to or to permit the movement of a train of gearing in the following manner, viz: Secured to or formed upon the 10 upper end of said reed are two pallets f and f, which are oppositely arranged and at such relative distance as to permit of the placing between of an escape-wheel K, which wheel is journaled upon a relatively-stationary sup- 15 porting plate or frame L, and is connected with a train of wheels that actuate register-hands M and M.

As preferably arranged, the vibrations of the reed F through the pallets f and f cause 20 the wheel K to have a step-by-step rotation and the registering mechanism to be actuated so as to show upon the dials thereof the number of such vibrations during a given time; but if desired said registering mechanism 25 may be driven by a spring or weight and its motion permitted and governed by the reed-actuated escapement.

It is intended that the vibrations of the reed F and the rotation of the escape-wheel 30 K shall be constant, and that connection between the latter and the registering-train shall be made or broken at the instant when the balance-vibrating mechanism is started or stops. This is preferably effected by means 35 of a wheel h, which is journaled upon one end of a pivoted bar O and supported in such position that while always meshing with one of the wheels P of the register-train it is capable of being moved into or out of engagement 40 with a wheel k upon the arbor of said escape-wheel by a movement of said bar. Opposite to the rear end of the bar O is placed an electro-magnet Q, which is connected with a source of electric energy, and such connection 45 opened or closed by means of or through the stop device that releases or arrests the operative mechanism for vibrating a balance, so that upon pressing the button E of the latter the current is cut off from said magnet 50 and said bar is free to be moved by a spring o so as to cause the wheels N and K to mesh and the registering-train to act, while when said stop device acts to arrest the motion of said balance-vibrating mechanism it also opens the 55 electric circuit and causes said magnet to move said pivoted bar in an opposite direction and thereby breaks the connection between the vibrating reed and registering-train, when the latter will instantly stop. 60 The hands of said registering mechanism are set at zero by means of the well-known devices employed for such purpose, which devices are operated by a push-button R.

In the use of the mechanism a balance is 65 placed in position and its vibrating mechanism released and the registering mechanism simultaneously started, after which

both will run until said balance has made the predetermined number of vibrations, when their motions will simultaneously cease. The 70 time required for the completion of the required number of vibrations of said balance will depend upon the weight of the latter, being less where the weight is light than where it is greater; but whatever the time required 75 such time is accurately noted by the registering mechanism in such fine divisions as to render easy the detection of very minute differences in the lengths of time covered by single vibrations of different balances. 80

It will be seen that the higher the rate of vibration of the reed the finer will be the divisions of time shown by the registering mechanism and the smaller the error in the balance which can be detected. It is practicable to secure twenty thousand vibrations of 85 said reed per minute, which will enable an error in the balance of one second in twenty-four hours to be shown.

For testing hair-springs precisely the same 90 mechanism is employed as that described, except that a standard balance instead of a standard hair-spring is secured upon the balance-arbor and provision made for the ready attachment and removal of the hair-springs 95 to be tried.

While the reed is preferably vibrated by electricity, the principle of its operation will be the same if a current of air or other means is employed for producing such motion, such 100 principle being the utilization of the absolutely synchronous movements of said reed for the measurement of time and for actuating and controlling registering mechanism or controlling such mechanism when otherwise 105 actuated.

The mechanism described is not claimed herein, the same being the subject of a separate application for patent filed February 13, 1890, Serial No. 340,320. The same apparatus we 110 herein show and describe is also shown and described in our application filed simultaneously herewith, Serial No. 324,821, and one filed February 13, 1890, Serial No. 340,321.

Having thus described our invention, what 115 we claim is—

1. The method employed for selecting watch-balances or hair-springs, which consists in vibrating the same a given number of times in connection with registering mechanism that 120 is controlled by a vibrating reed, substantially as and for the purpose specified.

2. The method employed for selecting watch-balances or hair-springs, which consists in vibrating the same a given number of times in connection, respectively, with a standard hair-spring or watch-balance and noting the length 125 of vibration by a vibrating reed-controlled registering mechanism, substantially as and for the purpose shown.

3. The method employed for measuring the relative lengths of vibration of watch-balances or hair-springs, which consists in causing the vibrations of a reed having a given pitch to 130

actuate or control a registering mechanism that is connected with the mechanism used for giving motion to such watch-balance or hair-spring, substantially as and for the purpose set forth.

4. As an improvement in the selection of the balances or hair-springs of a watch-motion, the method of controlling the movements of registering mechanism, which consists in causing a reed to vibrate at a predetermined pitch and communicating the move-

ments of such reed to such registering mechanism, substantially as and for the purpose shown and described.

In testimony that we claim the foregoing we have hereunto set our hands this 16th day of September, 1889.

GEORGE E. HUNTER.

FRED H. CORTHELL.

Corrections in Letters Patent No. 437,203.

It is hereby certified that in Letters Patent No. 437,203, granted September 30, 1890, upon the application of George E. Hunter and Frederick H. Corthell, of Elgin, Illinois, for an improvement in "Method of Adjusting Watches," errors appear in the printed specification requiring correction as follows: In line 35, page 2, the reference letter "h" should be *N*, and in line 51 same page the reference letter "K" should be *k*; and that the said Letters Patent should be read with these corrections therein to conform to the papers pertaining to the case in the Patent Office.

Signed, countersigned, and sealed this 7th day of October, A. D. 1890.

[SEAL.]

CYRUS BUSSEY,
Assistant Secretary of the Interior.

Countersigned:

C. E. MITCHELL,
Commissioner of Patents.
